(57) **CLAIM**

We claim the ornamental design for a die tool, as shown and described.

DESCRIPTION

FIG. 1 is a perspective of our new design for a die tool;
 FIG. 2 is a top view thereof;
 FIG. 3 is a front view thereof;
 FIG. 4 is a rear view thereof;
 FIG. 5 is a side view thereof, the opposite side view being a mirror image thereof; and,
 FIG. 6 is a bottom view thereof.

1 Claim, 6 Drawing Sheets
